BRACKET

Clarence E. Karst, Cincinnati, Ohio, assignor to
The Brunkhoff Manufacturing Company, Cincinnati, Ohio, a corporation of Ohio

Application March 31, 1936, Serial No. 71,913

4 Claims. (CL. 211—65)

This invention relates to improvements in supporting devices or holders, and is particularly directed to an improved bracket for mounting or holding a multiplicity of paint brushes or the like for display purposes.

It is the object of the present invention to provide a mounting or supporting device or bracket of this character, upon which a great many paint brushes or the like can be mounted and efficiently displayed, the structure of which is such as to preclude damage to or marring of the finish of the paint brush handles.

It is another object of the present invention to provide a bracket of this character which can be manufactured very inexpensively, and which is extremely durable and serviceable.

Other objects and further advantages will be more fully apparent from a description of the accompanying drawing, in which:

20 Figure 1 is a perspective view of the improved supporting device or bracket.

Figure 2 is a sectional view taken on line 2—2, Fig. 1, illustrating the bracket having a multiplicity of brushes mounted thereon.

25 Figure 3 is a sectional view taken on line 3—3, Fig. 2, further illustrating the device.

Referring to the drawing, a base or attachment plate 5 may be provided incorporating apertures 6, through which screws (not shown) may be inserted for fastening the plate to a wall. A hinge plate 7 is fixed centrally of the plate 5 by means of bolts 8. The hinge plate includes a diametrically arranged hinge portion 9 provided by ribbing the plate. When the hinge plate is fastened to the plate 5 or any other surface, a generally circular passage results, within which the hinge portion of the bracket element 10 is disposed.

30 The bracket element 10 is formed of heavy wire looped to provide parallel arms 11, 11. The loop portion 12 is bent at right angles to the arms as at 13 and includes the cross portion 14 disposed through the bore or passage formed by the hinge plate. By virtue of the above arrangement, the 35 loop end 12 of the bracket 10 lies against the plate in its position of suspension from the hinge plate and the arms extend or project outwardly at right angles to the plate.

40 Sleeves 15 are engaged over the arms. These sleeves are formed of some pliable or soft material such as rubber. The ends of the arms are turned as at 16 to prevent displacement of the sleeves. As illustrated in Figures 1 and 3, the throat provided between the bushings is of a width suitable for receiving the narrow portions 17 of the shanks of the paint brushes 18. Each paint brush is therefore supported or suspended because of

the inability of the enlarged end thereof to pass downwardly between the arms of the bracket.

Brushes can be quickly and efficiently placed on the bracket simply by sliding them into the throat or space between the arms of the bracket. By 5 the use of this device, a great many brushes can be supported and efficiently displayed, stored or dispensed.

Having described my invention, what I claim is:

1. A support bracket for paint brushes or the like, consisting of a base plate and a bracket element hinged to the face of the base plate, said bracket element providing parallel arms open at their outer ends and connected at their inner ends to provide a hinge portion and including 10 rubber sleeves on the arms for protecting the finish of the devices mounted between and on the arms, the hinged end of the bracket being angularly formed, said angularly formed end of the bracket abutting against the face of the base 15 plate for disposing the arms in positions projecting outwardly at right angles from the plate.

2. A support bracket for paint brushes or the like, consisting of a base plate and a bracket element hinged to the face of the base plate, said 20 bracket element providing parallel arms open at their outer ends and connected at their inner ends to provide a hinge portion, the hinged end of the bracket including an angular portion abutting 25 against the face of the plate for disposing the 30 arms in positions projecting outwardly at right angles from the plate.

3. A support bracket for paint brushes or the like, consisting of a base plate and a bracket element hinged to the face of the base plate, said 35 bracket element providing parallel arms open at their outer ends and connected at their inner ends to provide a hinge portion and including protective sleeves thereon, adapted to resiliently engage the articles mounted therebetween, the supported end of the bracket being angularly formed 40 for abutting against the plate for disposing the arms in positions projecting outwardly at right angles from the plate.

4. A support bracket for paint brushes or the like, consisting of a bracket element, said bracket element providing parallel arms open at their outer ends and connected at their inner ends to provide a hinge portion and including rubber 50 sleeves on the arms for protecting the finish of the devices mounted between and on the arms, the hinged end of the bracket being angularly formed, the angular portion abutting the face of the plate for disposing the arms in positions projecting outwardly at right angles from the supporting surface.

CLARENCE E. KARST.
